GAS TURBINE

Arthur H. Matthews, Lake Beauport, Quebec,
Canada

Application July 5, 1944, Serial No. 543,574

2 Claims. (Cl. 60—41)

1

This invention relates to gas-turbines and the object is to provide a simple and efficient gas-turbine which may be constructed of ordinary inexpensive metals and in which provision is made for adequate cooling with minimum loss of power and efficiency.

The commercial development of cheap and efficient gas-turbines, especially in the smaller sizes required for general use, has been retarded by reason of the fact that the best gas-turbines heretofore proposed must be constructed of relatively rare and expensive heat resistant metals or alloys in order to withstand, for any considerable period, the destructive action of the high operating temperatures characteristic of such turbines. Gas-turbines constructed of ordinary metals and equipped with heat-dissipating water jackets in accordance with previous proposals do not have the operating speed, efficiency, low-cost characteristics and other essential requisites necessary to justify wide-scale commercial production thereof, especially in the smaller sizes suitable for general use in various fields in which other types of relatively small power plants are now being used.

An important feature of the gas-turbine provided in accordance with my invention is that the rotor is of simple design and is free of vanes, buckets, or other resistance-increasing projections which, as employed in prior types of gas-turbines, tend to decrease both the operating speed and the power output.

Another feature of the invention consists in the provision of a generally improved gas-turbine in which the use of ordinary metals is made feasible by the use of water jets which serve both as a cooling medium and as a motive fluid.

A still further feature of the invention consists in the provision of a jet-propelled or reaction-type gas-turbine in which the rotor comprises a simple disk-shaped element provided with a peripheral channel into which jets of motive fluid are directed from nozzles or jets carried by a stator casing in which the rotor operates, at least one side wall of said channel being provided with discharge openings through which the motive fluid is supplied to said channel in the form of jets which impinge against stationary buckets or vanes carried by the stator casing.

Other characteristic features and advantages of my invention will be made apparent by the following detailed description of the accompanying drawing, in which—

Fig. 1 is a vertical sectional view taken substantially along the line 1—1 of Fig. 2; and

2

Fig. 2 is a sectional view taken substantially along the line 2—2 of Fig. 1.

In this drawing the rotor and the stator-casing elements of my improved gas-turbine are respectively indicated at 5 and 6.

The rotor 5 is shown as a simple disk fixed to a shaft 7 which rotates in bearings 8 carried by opposite side walls of the stator-casing 6. The periphery of the rotor is recessed to provide an annular channel 9 into which jets of fluid are directed from nozzles or jet passages 10, 11 and 12 formed in a removable section 6a of the stator casing 6. At least one side wall of the channel 9 is provided with discharge ports 14 through which jets of the motive fluid supplied to said channel are discharged against suitable stationary vanes or buckets 15 arranged around the upper half of stator-casing 6 to thereby effect jet-reaction operation of the rotor. The motive fluid is discharged from stator-casing 6 through the exhaust outlet 17.

Part of the motive fluid supplied to the channel 9 of rotor 5 comprises hot products of combustion resulting from ignition of a combustible fuel mixture with a combustion chamber 18 provided in the removable cylinder section 6a. The fuel mixture is supplied to chamber 18 through a "Tesla" valve 20 and is ignited by a spark plug 21 or other suitable igniter. The resulting products of combustion escape from chamber 18 through jet passage 16 and are directed into the rotor channel 9.

Another part of the motive fluid supplied to the rotor consists of steam formed by vaporization of jets of water which are directed into the rotor channel 9 by the jet passages 11 and 12. The cooling action of these jets of water is sufficient to prevent heat-destruction of ordinary metal used in the construction of the turbine. The water is preferably supplied to the jet passages 11 and 12 through "Tesla" type valves indicated at 22 and 23.

The peripheral wall of the stator casing 6 is provided with a series of expansion chambers 25 into which the steam resulting from vaporization of the water jets directed against the rotor is expanded to increase the momentum imparted to the rotor.

The hot products of combustion directed into the rotor channel 9 by nozzle 10 constitute the main motive fluid which drives and heats the rotor. The water injected through the jet passages 11 and 12 serves primarily as a cooling medium but, when converted into steam as described herein, also serves as a motive fluid and enables

the turbine to be operated efficiently with a smaller amount of combustible fuel than would otherwise be required.

The combustion chamber 19 is provided with a removable cover or head 26 formed with a water jacket 27 which is connected, by pipe 28, to water-jet valve 22. Cooling water is supplied to jacket 27 by a suitable supply pipe (not shown) and passes from thence through pipe 28 and valve 22 to water-jet passage 11. The valve 23 of water-jet passage 12 may be similarly connected to water jacket 27.

Having thus described what I now conceive to be the preferred embodiment of my invention it will be understood that various modifications may be resorted to within the scope and spirit of the invention as defined by the appended claims.

I claim:

1. A gas-turbine comprising a rotor provided with a peripheral channel having discharge ports in one side wall thereof, a stationary casing enclosing said rotor and provided with jet-passages through which expansible motive fluid is directed into said channel and stationary vanes or buckets in said casing located opposite the ported side of said channel and positioned to receive the impact of jets of motive fluid discharged from said channel through said ports.

2. A gas-turbine as set forth in claim 1, in which said rotor comprises a simple, substantially disk-shaped member having its periphery recessed to provide said channel.

ARTHUR H. MATTHEWS.
